UNITED STATES PATENT OFFICE.

MARY THOMAS PERRY, OF TAMPA, FLORIDA.

SANITARY GARBAGE RECEPTACLE.

Application filed October 24, 1927. Serial No. 238,318.

The primary object of this invention is to provide a self-sustaining garbage receptacle of destructible waterproof and acidproof material, which is to be carried away with the 5 garbage and not used a second time.

A secondary object is to provide such a receptacle as will prevent the escape of obnoxious odors and which will be sealed against the entry of insects and the like.

10 With these and other equally important objects in view, reference will be had to the accompanying drawing, which forms a part of this specification and wherein like reference characters designate corresponding parts 15 throughout the several views, in which:

Fig. 1 is a vertical sectional view of the invention,

Fig. 2 is a similar view of the upper portion thereof, and

20 Fig. 3 is a similar view, with parts shown in perspective.

In the drawing, reference numeral 1 designates the body of the receptacle, which is formed of waterproof and acidproof material 25 such as paper or papier mâché, and 2 represents the bottom thereof, which may be formed integrally or separately, the latter forming no material part of the invention.

The sides of the receptacle, diverge upwardly to form a pail-like member, which is provided near its upper edge with a bead 3, the same being rolled or molded to shape. Beyond this bead 3, the sides continue into an exposed rim portion 4, which is provided at 35 diametrically opposite points with horizontally elongated openings 5, to receive the fingers of the hand of the user or garbage collector in transporting the receptacle.

A cover 6 in the form of a disk, preferably 40 of the same material as the body, when in closing position, rests upon the bead 3, tightly fitting the inner sides of the rim portion 4 and closely hugging the bead 3. At diametrically opposite points, this closure disk 6 is 45 provided with upwardly extending tabs 7, which are provided each with an opening 8.

In using the receptacle, the garbage is placed therein and the cover is applied, and when it reaches the position illustrated in 50 Fig. 3, its edges begin to snugly engage the sides of the rim portion 4, and from then on to its final position on the bead 3, considerable force must be applied around its marginal edge to force it to place. The tabs 7 afford a

convenient means for first applying and removing the closure, each tab being engaged between the thumb and fingers of the hand, with a finger partially or entirely entered in the opening 8, the tab being long enough to set away from the rim portion 4 for the accommodation of the fingers between the same and the rim portion 4. Obviously, an instrument could be engaged in the opening 8 instead of the finger. When the closure is in place, the same occupies a plane below the bottom of the openings 5 to fully expose the same as handle elements.

Garbage, when placed directly in metal containers, adheres to the sides and bottom thereof and the said content thereof attacks the 70 metal, furthermore, the closures of metal garbage containers seldom have a tight fit and for that reason permit the offensive odors from the garbage to escape as well as permitting ready access of insects and the like 75 to the contents of the receptacle, affording a very unsanitary condition of affairs. When, instead of placing garbage in a metal receptacle, in direct contact with the metal sides thereof, paper linings are provided, the same 80 depend for sustaining qualities upon the support of the receptacle, usually by being attached in some way to the upper edges of the receptacle, but such a lining, beside not being self sustaining and independent of the metal 85 container, is incapable of receiving a tightly fitting closure member, which is capable of ready insertion and removal finally or at different times for the placement of garbage in the receptacle.

It is further pointed out that the receptacle and its closure member, being formed of paper or the like, may be carried away and disposed with the garbage, and forms no obstacle to destruction of the garbage by the 95 usual methods, and in the case of destruction by incineration is a distinct aid thereto owing to the nature of the waterproofing material, which in this case is paraffin.

Thus, by the use of this invention, it is only 100 necessary to have a stack of nested pails from which one is removed when needed, avoiding the constant presence of a receptacle on the floor. These receptacles are made in different sizes so that a size may be selected according to the requirements of each meal prepared, after which, the receptacle is sealed by applying the cover and the receptacle placed out-

side for collection, the collector depositing the same in the collection vehicle and carting it away to the point of disposal.

What is claimed:—

- 5 A self sustaining garbage receptacle formed of combustible material, and comprising a body having diametrically opposite handle openings, a bead formed around the side wall of said receptacle below said opening, a closure member tightly engaged with the side wall and resting on said bead and oc-
- 10

cupying a plane below said handle openings, and apertured tabs extending upwardly from diametrically opposite points on the edge of said closure member and adapted to permit ¹⁵ the insertion of the fingers of the hand between the same and the side wall of the receptacle, the upper edges of the tabs positioned below the upper edge of the receptacle.

In testimony whereof I affix my signature.

MARY THOMAS PERRY.
